UNITED STATES PATENT OFFICE.

HEINO L. GOEHDE, OF BROOKLINE, MASSACHUSETTS.

DESIGN FOR AN AUTOMOBILE.

60,657.

Specification for Design.

Patented Mar. 21, 1922.

Application filed June 17, 1920. Serial No. 389,766. Term of patent 3½ years.

To all whom it may concern:

Be it known that I, HEINO L. GOEHDE, a citizen of the United States, residing at Brookline, in the county of Suffolk and State of Massachusetts, have invented a new, original, and ornamental Design for an Automobile, of which the following is a specification, reference being had to the accompanying drawing.

The accompanying drawing illustrates a side elevation of the new design.

I claim:

The ornamental design for an automobile as shown.

HEINO L. GOEHDE.
